(57) **CLAIM**

The ornamental design for a chandelier arm, as shown and described.

DESCRIPTION

FIG. 1 is a perspective view from below of a chandelier arm in accordance with our design;

FIG. 2 is a top plan of the chandelier arm in accordance with our design;

FIG. 3 is a bottom plan view of the chandelier arm in accordance with our design;

FIG. 4 is a front plan view of the chandelier arm in accordance with our design;

FIG. 5 is a back plan view of the chandelier arm in accordance with our design; and,

FIG. 6 is a side elevation view of the chandelier arm, the opposite side being a mirror image of that shown.

The broken lines showing environmental structure are for illustrative purposes only and form no part of the claimed invention.
